(57) CLAIM

The ornamental design for a gaming tower console, as shown and described.

DESCRIPTION

FIG. 1 is a perspective view of a gaming tower console showing my new design, wherein the placement of the logo or other indicia are shown in broken lines for illustrative purposes only and form no part of the claimed design

FIG. 2 is a rear view thereof;

FIG. 3 is a front view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are for illustrative purposes only and form no part of the claimed design.
